The ornamental design for a two tone storage bin, as shown and described.

DESCRIPTION

FIG. 1 is a rear perspective view of a first embodiment of a two tone storage bin showing the new design;

FIG. 2 is a rear elevational view thereof;

FIG. 3 is a front elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear perspective view of a second embodiment of the two tone storage bin, the second embodiment being identical to the first embodiment except for the addition of a divider wall in the center thereof;

FIG. 9 is a rear elevational view thereof;

FIG. 10 is a front elevational view thereof; and,

FIG. 11 is a top plan view thereof.

The stippling that can be seen on the rear portion of the claimed design is a type of shading that represents a type of surface material.

The broken lines are for the purpose of illustrating the environment of the article only and form no part of the claimed design.
